(57) **CLAIM**

The ornamental design for an equine protective leg boot, as shown and described.

DESCRIPTION

FIG. 1 is a front perspective view of an equine protective leg boot, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is the equine protective leg boot in an expanded state; and,

FIG. 10 is an enlarged detail view of area 10 in FIG. 1. The broken lines in the drawings illustrate the portions of the equine protective leg boot, which form no part of the claimed design.

The long dash-long dash-dot broken lines in FIGS. 1 and 10 show the boundaries of the enlargement shown in FIG. 10 and form no part of the claimed design.
